HAIR CLIPPER ATTACHMENT

William O. Yancey and Virgil L. Yancey,
San Francisco, Calif.

Application January 24, 1934, Serial No. 708,158

2 Claims. (Cl. 30—1)

This invention relates to improvements in hair clippers and has particular reference to a comb arrangement for attachment to the customary hair clipper used by barbers.

5 A further object is to produce a device which is light weight and, therefore, one which will not upset the balance of the usual clipper and a device which will remain fixed irrespective of vibration.

10 Another object is to produce a device which will not become entangled with the hair and will be smooth when brought against the scalp.

An additional object is to produce a device which is neat in appearance.

15 A further object is to produce a device which is economical to manufacture and one which may be sold at a reasonable price to the average barber.

20 A further object is to produce a device where- in the length of cut given the hair may be readily changed in cutting different parts of the hair on the head.

25 A still further object is to enable the barber to cut hair with a clipper in such a manner that the usual marks left by the clipper will be entirely eliminated.

Other objects and advantages will be apparent during the course of the following description.

In the accompanying drawings forming a part 30 of this specification and in which like numerals are employed to designate like parts throughout the same,

Fig. 1 is a side elevation of our device,

Fig. 2 is a bottom plan view of Fig. 1,

35 Fig. 3 is a fragmentary side elevation, a portion thereof being shown in cross section, and showing the comb in central position,

Fig. 4 is a view similar to Fig. 3 showing the comb in advanced position,

40 Fig. 5 is a perspective view of the comb retaining clip,

Fig. 6 is a cross section taken on the line 6—6 of Fig. 4,

Fig. 7 is a perspective view of the retainer,

45 Fig. 8 is a rear elevation of the comb, and

Fig. 9 is a front elevation of the comb and shown partly in cross section.

Barbers, in cutting hair, ordinarily employ a pair of clippers, either hand or electric, for the 50 initial trimming. Afterwards they usually employ a comb and scissors with which the final cut of the hair is accomplished, the reason being that the ordinary clipper leaves marks, for the reason that it has but a single adjustment 55 and when held against the head only a certain

length of hair can be left upon the head, that is, without tipping the clippers upon their heel, which is virtually impossible to accomplish when it is considered that the hand is moving over a rounded contour. Applicants have, therefore, devised an attachment which may be secured to any clipper, which attachment will permit the employment of the clipper for cutting the hair at any point upon the head and without leaving objectionable clipper marks.

5 Applicants employ an ordinary clipper designated as a whole by the numeral 5, having a reciprocating cutter 6 and a home plate 7. The construction thus far is common to all clippers and forms no part of our invention.

10 Our invention includes a wire clip 8 having an offset 9 spaced from the back of the clipper body and adapted to be engaged by the hooked end 11 of a sliding retainer 12. This retainer is mounted upon a finger piece 13 and is held in sliding contact therewith by a pin 14 which also retains a spring 16. Notches 17 formed on the finger piece also engage the offset portion 9 of the wire 8. This finger piece has a nose 18, which is adapted to engage notches 19, 21 and 25 22 of a comb arrangement 23. This comb arrangement is provided with teeth 24 adapted to overlie the teeth of the home plate and the sliding cutter 6. This comb is, therefore, slidable on the home plate and held in adjusted position 20 by the finger piece 13 which will be later described. A lever 26 is attached to the comb and lies parallel with the side of the clipper (see Figs. 1 and 8). This lever extends through the comb and has a crank 27 formed within its length. 30 The crank is so positioned that it may be caused to move against the back of the home plate for the purpose of separating the home plate from the comb.

35 Referring now to Fig. 1, it will be noted that the finger piece is so arranged that its nose is in the slot 19. Therefore, the comb is back of the teeth of the home plate and consequently a very close fit between the parts exists. If the barber now uses the device, the teeth of the home 40 plate and the clipper may be brought very close to the head and the resulting hair cut will be termed short. If the comb is now moved by pressing upon the finger piece 13 so that the nose engages the slot 21, then the parts will be in 45 the full line position of Fig. 3. The moving forward of the comb will cause a slight space at the point A, that is, between the teeth of the comb and the teeth of the home plate. Thus the hair 50 cut will be somewhat longer than that in Fig. 1. 55

Now if it is desired to make further adjustment the user may press the thumb against the lever 26 so as to press the lever in the direction of the arrow of Fig. 3, and thus move the parts from the full line position to the dotted line position. It will be apparent that the space at the point A is thus considerably increased and when it is considered that this increase is gradually accomplished by the movement of the thumb it will be apparent that a gradual tapering of the hair length is accomplished. In Fig. 4 we have illustrated the tip of the finger piece as engaging the slot 22, thus moving the comb a considerable distance along the surface of the home plate and thus increasing the space at the point A which space can again be gradually increased by the manipulation of the lever 26.

It will be noted that when the tip of the finger piece engages the slot 19 or in other words when the comb is in retracted position and the teeth thereof in back of the home plate teeth, the device will readily serve as a clipper and will positively remove the line.

It will, therefore, be apparent that any desired adjustment may be accomplished through the employment of our device, thus eliminating the necessity of employing several clippers as is now often done.

It is to be understood that the form of our device herewith shown and described is to be

taken as a preferred example of the same and that various changes relative to the material, size, shape and arrangement of parts may be resorted to without departing from the spirit of the invention or scope of the subjoined claims. 5

Having thus described our invention, we claim:—

1. In combination with a clipper having a body portion, a reciprocating cutter and a home plate, a finger piece pivotally secured to said body portion, a comb mounted on said home plate and adjustably held by said finger piece, means for moving a portion of said comb away from said home plate, said means including a lever and a crank, said crank being spaced between the comb 15 and said home plate whereby movement of said lever causes a camming action between said comb and said home plate.

2. In combination with a clipper having a body portion, a reciprocating cutter and a home plate, 20 a comb slidable on said home plate, said comb having a plurality of grooves formed therein, a finger piece adapted to engage one of said grooves, and manually operated means adapted to move said comb away from said home plate at a point 25 remote from the engagement of said finger piece with said groove in said comb.
